PICTURE FRAME

Ozro M. Goodwin, Lynn, Ark.

Application February 15, 1954, Serial No. 29,016

Term of patent 14 years

(Cl. D29—20)

To all whom it may concern:

Be it known that I, Ozro M. Goodwin, a citizen of the United States, residing at Lynn, in the county of Lawrence and State of Arkansas, have invented a new, original, and ornamental Design for a Picture Frame, of which the following is a specification, reference being had to the accompanying drawing, forming part thereof.

In the drawing:

Fig. 1 is a front elevational view showing my new design for a picture frame;

Fig. 2 is a top plan view thereof, and

Fig. 3 is a side elevational view thereof.

The dominant features of the design reside in the portions shown in full lines.

I claim:

The ornamental design for a picture frame, substantially as shown and described.
